FURNACE CONSTRUCTION

Robert C. Denny, Chicago, Ill., assignor to M. E. Detrick Company, Chicago, Ill., a corporation of Illinois

Application July 18, 1931, Serial No. 550,860

24 Claims. (Cl. 110—1)

This invention relates to furnace construction, and it pertains particularly to furnaces of large size, such as boiler furnaces, that are fired by burners arranged to inject powdered, liquid or gaseous fuel through appropriate burner openings in the furnace wall.

A general object of the invention is the provision of improved construction for furnace wall portions arranged to provide burner openings. 10 A more particular object is the provision of such construction adapted to withstand effectively the furnace heat and erosive influences to which it is subjected in use, which may be assembled and repaired with facility, and which is particularly qualified to withstand the vibration or pulsations quite generally produced in such 15 portions of the furnace incident to operation of the burners.

Another particular object of the invention is 20 the provision of such a construction employing comparatively small sized pre-formed refractories, and wherein the refractories are definitely retained in the desired position and relation in the structure in such fashion that they may 25 have a desired mobility or adjustability with respect to one another and with respect to retaining parts, to avoid their being subjected to destructive pressures.

Another object is the provision of such a construction suitable for forming a solitary burner opening or a plurality of burner openings in association.

Other and further objects will be pointed out or indicated hereinafter or will be apparent to one skilled in the art upon an understanding of the invention or its employment in practice.

For the purpose of aiding in a full disclosure of the invention, I illustrate in the accompanying drawings, and hereinafter describe, certain structures as examples of embodiment of the invention, but it is to be understood that these are presented merely for purpose of illustration, and hence are not to be construed in any fashion calculated to limit the appended claims short of the 45 true and most comprehensive scope of the invention in the art.

In said drawings,

Fig. 1 is a sectional elevational view of a portion of furnace wall and associated burner parts 50 showing two burner openings, one disposed above the other, the section being taken along the vertical diameter of the burner openings;

Figs. 2, 3 and 4 are perspectives illustrating three forms of refractories employed in the construction illustrated in Fig. 1;

Fig. 5 is an elevational view of the inner side of the wall construction at a burner opening, the right hand half of the figure having the refractories removed for the purpose of showing frame portions; 60

Fig. 6 is a sectional view looking at the left hand side of Fig. 5;

Fig. 7 is a broken perspective view of a modified construction;

Fig. 8 is a perspective illustration of another 65 refractory; and

Fig. 9 is a perspective illustration of a hanger bracket.

There are various types of burner or fuel feeding apparatus employed for the firing of large 70 furnaces by injection of powdered fuel, oil, or gas, together with primary combustion air, through burner openings in the furnace wall. It is usually necessary that the so-called burners or nozzles from which the fuel is discharged be positioned a substantial distance from the inner side of the wall, in order that they may be protected from the furnace heat in so far as possible. In most large furnaces the wall in which the burner opening is located usually has to be of 75 quite substantial thickness in order to withstand the heat and possess the desired heat confining character, and the burner openings have to be of considerable size in order to afford the requisite capacity for introduction of fuel and air, and the thickness of the wall necessarily involves their being of considerable length. The provision of burner openings, particularly openings of circular or curved contour, through the refractory walls of large furnaces has presented serious 80 difficulties, as shown in the rather frequent failure of the refractory wall portions which are in association with or which bound such burner openings. The portions at the inner side of the furnace wall are subjected to much higher heat 85 than those portions toward the outer side of the wall, and are subject to much greater thermal expansion. The wall portions in association with the burners, moreover, are usually subjected to very appreciable vibration or pulsations attendant upon the operation of the fuel injecting apparatus. These circumstances have rendered it quite difficult to provide a construction which will have sufficient stability and security to withstand the vibrations over long periods, and at 90 the same time possess sufficient flexibility to accommodate the differences in thermal expansion between interior and outer parts. The present invention provides a construction wherein pre-formed refractories of moderate size are assem- 95

100

105

110

115

120

bled in a relationship affording an opening of the desired form, the refractory structure being supported on an external frame positioned outside the high temperature zone of the furnace, and 5 the refractories being anchored in place in such fashion that they will retain the desired relationship and positions, but may have a limited freedom of individual movement, giving the structure a desirable internal flexibility which accommodates 10 expansion and contraction and safeguards its component parts against destructive pressures. Superjacent portions of the furnace wall are supported in such fashion that their weight is not imposed upon the refractories which bound 15 the burner opening, and these latter are likewise supported in such fashion that their weight is not imposed on the refractories in subjacent wall portions or those which form subjacent or laterally associated burner openings. The construction is 20 such that the entire refractory structure involved may be built of pre-formed refractories, thus eliminating any necessity for piecing or patching with plastic material.

The nature of the invention will be understood 25 in more detail by reference to the examples illustrated in the drawings. In Fig. 1 the reference numeral 10 designates one of a plurality of upright frame members, which are disposed along the furnace wall and constitute the main supporting 30 element thereof. Suitable plate portions 11 are attached to the inner flanges of the members 10 and are supported thereby in a vertical plane, these plate portions being shaped at the margins to afford openings corresponding to the 35 location of the burner openings. In the examples here illustrated these boundary margins are arcuate so as to conform to a round burner opening. At these openings is a cast iron ring 12, which may be formed in segments and bolted through 40 the plate portions and to the flanges of the burner collar 15, which is positioned outside the wall and suitably supported, as on the frame. At its inner end the ring 12 is flanged to provide the inwardly presented shoulder 12^a and the longitudinally presented ledge 12^b. Above and below 45 the ring 12, horizontally extending angle members 16 are secured to the plate members 11 and have at their inner margins flanges disposed in a vertical plane. At opposite sides of the ring 12 cast iron anchor bars 17 (see Figs. 5 and 6) are 50 supported in vertical position on angle seats 18 and the subjacent members 16. These anchor bars have spaced laterally projecting lugs 17^a extending from their inner margins. Flanged angle 55 members 19, like the members 16, are secured in diagonal or sloping position adjacent the ring 12, as illustrated in Fig. 5, being bolted to the plate member.

The furnace wall portions above and below 60 and alongside the burner opening structure are made up of refractories 20 supported on the frame structure by means of hangers 21 as in the fashion illustrated in the U. S. Patent to Frank I. Sheahan, No. 1,875,667, the weight of these 65 refractories being taken by the shelves 21^a of the hangers, and their outer ends are spaced from the plate members 11 so as to afford an intervening air circulating space. The refractories which bound the burner opening comprise 70 inner refractories 22, 24 and 25 and outer refractories 26. The refractories 22 and 24 are of the same form, but shaped as lefts and rights. Their lateral faces 24^a converge from the outer face 24^b, so that they are wedge shaped, and 75 their inner margin is irregular so as to afford

a convex portion 24^c and a notched portion 24^d. Their outer sides are notched at the outer end to provide an in-set portion 24^e and a pocket 24^f, and an arcuate groove 24^g is provided across their outer ends. The refractories 25 (Fig. 3) are of similar form, but their outer sides are anticlinal as shown. The outer refractories 26 (Fig. 4) have their inner ends shaped to fit in the notched portion 24^d of the refractories 22, 24 and 25, so that their convex inner surfaces 26^a will coalesce with the curved inner surfaces 24^c of the inner refractories. They also have the notches 26^b and 26^c extending across their outer faces. The wedge form of the refractories 22, 24 and 25 is such that when disposed in the order illustrated in Fig. 5 with the lateral faces of juxtaposed ones in abutment, they will form a complete collar. In assembly, those at the bottom of the burner opening are supported on the ledge 12^b of the ring, and on bracket hangers 27. These bracket hangers are cast iron members having ledge portions 27^a with anchor lugs 27^b thereon, and hook portions 27^c adapted to engage over the upper flanges of the members 16 and maintain the bracket hangers theron with the ledge 27^a in a horizontal position. The ledge portion of a bracket hanger is accommodated by the notched portion 24^d of the refractory, the lug 27^b extending into the pocket 24^e and serving to prevent withdrawal of the refractory inwardly from the ledge portion. The groove 24^g of each refractory accommodates the shoulder portion 12^b of the ring. Similar bracket hangers are likewise mounted on the diagonal angle members 19 and hold the refractories 22 and 24 which are next above the four lowermost in the assembly. The next four refractories, at each side of the assembly, are anchored in place by engagement of the lugs 17^a of the hanger bars in their pockets, as illustrated in Figs. 5 and 6, the weight of these refractories being supported in part thereby and in part by the ones therebelow. The next two refractories on each side are anchored in place by hanger brackets which are supported on the upper diagonal angle members 19, while the four refractories in the crown of the assembly are supported on the shoulder 12^b of the ring and anchored in place by hanger brackets connected to the upper angle members 16. The refractories 26 are supported by the ring 12, and anchored in place by engagement of the ring shoulder 12^a in the grooves 26^b, the inner ends of said refractories fitting in the notched portions 24^d of the inner refractories. As observed in Fig. 5, 130 the shoulder portion 12^a is omitted at the top portion of the ring, so that the two refractories 26 at the top of the assembly may be slid directly into place before the two uppermost refractories 22 and 24 are put in place, these two uppermost 135 refractories 26 being held by said inner refractories against displacement inwardly. The length of the refractories 22, 24 and 25 is such as to correspond approximately to the desired thickness of the refractory wall, so that 140 their inner ends will lie in approximately the same plane as the inner wall surface, and their outer ends will be spaced from the plate members 11 so as to afford an air circulation space. The length of the refractories 26 is such as to extend across this air space and across the ring 12, so that when the assembly is completed they form a sleeve extending outwardly from the refractory wall as the boundary of an outward continuation of the burner opening. The intended 150

burner devices B are mounted in the desired association with the burner opening so afforded so that the fuel and combustion air may be injected into the furnace through the burner opening.

It will be observed that by virtue of the construction the burner opening is defined by a continuous refractory collar or sleeve which gives the opening the desired contour and which is made up of a plurality of relatively small refractories. It will be observed that all of the refractories are definitely anchored in place in such fashion that they are held against shifting inwardly or outwardly out of the desired association with one another, but at the same time have a limited extent of individual movement. This limited mobility is afforded by a certain amount of play or loose fit between the refractories and their anchoring members, the various 20 grooves and pockets of the refractories being of sufficient size to admit such play on the anchoring portions 12^a, 12^b, 17^a and 27^b. It will be observed, moreover, that the refractory collar or sleeve formed by the assembled refractories is, 25 in a sense, flexible due to the permissible mobility of the inner refractories with respect to the outer refractories, so that differences of expansion as between the inward portions of the structure and the outward portions of the same are 30 quite freely accommodated and the integrity and continuity of the refractory structure thus preserved and the refractories safeguarded against fracture.

Inasmuch as the refractory collar thus formed by the refractories 22, 24, and 25 is of generally octagonal peripheral outline, whereas the contiguous portions of the wall structure run on horizontal and vertical lines, there remain triangular portions which must be fitted with regular refractories. These portions are fitted with the triangular refractories 28, which are formed at their outer ends with the grooves and pockets 28^a in which lugs 27^b of some of the hanger brackets and lugs 17^a of the hanger bars are 40 engaged, as illustrated in Figs. 5 and 6, to anchor these triangular refractories in place. Outwardly from the wall, and facing the wall portions in which the burner openings are located, are casing plates or the like 30 which form portions of an enclosure that functions as a wind box for the supplying of primary combustion air to the burner openings, this wind box affording ample space for the free circulation of air in contact with the portions of the frame members 50 which are enclosed therein, for cooling effect. Air inlets 31 are provided at suitable locations for admission of external air into the air circulating space between the plate 11 and the outer ends of the refractories, said air being free to flow upwardly in contact with the wall refractories and the burner opening refractories and in contact with the various metallic supporting and anchoring members 21, 27, 12, 16, etc., for cooling effect, said air passing out of 60 the air space through suitable openings at the top of the structure. By this provision for cooling, the metallic members are safeguarded against rapid deterioration by heat, and the life of the refractories is likewise augmented.

The assembly shown in Fig. 7 illustrates a somewhat modified construction, in which the burner ring 12' is mounted on supplementary frame members 13 and the outer refractories 26' are of such length as to extend inwardly across 70 such supplementary frame members and across

the air space at their inner side, said refractories resting at their inner ends within the notched portions of the inner refractories 23 and at their outer ends within the channel of the ring 12'. The inner refractories, as in the form first described, are supported and anchored in position by hanger brackets 27' clamped to the supplementary frame members 13. In this illustration the refractory collar is shown as of cylindrical form instead of inwardly flaring form as in the previous example, and has transverse flexibility and mobility of its component refractories such as to accommodate differences of expansion as between inward and outward parts of the structure.

What I claim is:

1. Furnace structure comprising, in combination, a wall-supporting frame, refractories supported by said frame but spaced therefrom to form a furnace wall, inner wedge shaped refractories supported by and anchored to the frame and disposed in the plane of said wall in association to form a ring encircling a burner opening through the wall, and other wedge shaped refractories supported by the frame and associated with said inner wedge shaped refractories to form extended walls for said burner opening continuing outwardly from the inner wedge shaped refractories.

2. In furnace construction, the combination 105 of a wall-supporting frame, refractories supported by said frame to form a furnace wall spaced therefrom to afford an intervening air space, inner wedge shaped refractories supported by and anchored to the frame and disposed in the 110 plane of said furnace wall in association to encompass an opening therethrough, and outer refractories supported by the frame with their inner ends in association with said inner refractories, said outer refractories extending outwardly across the air space in association to form outwardly continuing walls for said opening.

3. In furnace construction, in combination, a wall-supporting frame, refractories supported by the frame to form a furnace wall spaced therefrom, inner refractories supported by the frame in association to form a collar affording a passage through the furnace wall, and outer refractories supported by the frame in association with said inner refractories to form a sleeve extending outwardly from said inner refractories and affording an outward extension of said passage.

4. A furnace wall structure comprising, in combination, a wall-supporting frame, wedge shaped refractories supported by said frame and anchored thereto in association to form a collar spaced collaterally from the frame and constituting the boundary of a wall opening, and outer refractories supported by the frame with their inner ends adjoining said wedge shaped refractories and their outer portions extending outwardly therefrom, said outer refractories being associated to form the boundary of an outward extension of said wall opening.

5. In a furnace wall, in combination, an external wall-supporting frame, wedge shaped refractories supported thereby to form a collar bounding a wall opening with the divergent faces of said refractories extending radially from said opening, means anchoring said refractories to the frame, and refractories supported by the frame independently of said collar to form a wall portion adjoining and continuing upwardly from said collar.

6. In a furnace wall, in combination, a frame at 150

- the outer side of the wall, a ring supported by and extending inwardly from the frame toward the furnace chamber, refractories arranged to form a collar encompassing a wall opening and having 5 their outer ends within said ring, said refractories extending inwardly toward the furnace chamber from said ring, and means anchoring said refractories against displacement longitudinally of said wall opening.
- 10 7. Furnace wall structure as specified in claim 6 and including inner refractories contacting the inner ends of said first mentioned refractories and extending therefrom inwardly toward the furnace chamber and means anchoring said inner refractories to the frame to prevent their displacement inwardly.
8. In a furnace wall, in combination, a frame, refractories supported thereby but spaced inwardly therefrom and arranged to form the 20 boundary of a wall opening, said refractories having notched outer end portions, and other refractories seated in said notched portions and extending outwardly toward the frame to form an extension of said wall opening boundary.
- 25 9. A furnace structure comprising, in combination, a frame disposed externally of the furnace chamber, a burner ring supported thereby, a refractory wall supported on the frame but spaced inwardly therefrom to afford an intervening air 30 chamber, outer refractories supported at their outer ends on the burner ring and extending across said air chamber, said outer refractories arranged to form a collar bounding a burner opening, inner refractories supported in the wall to 35 form a collar portion bounding a continuation of the burner opening through the wall, and means anchoring the inner refractories to the frame to retain them in the wall but permitting them limited individual movement relative to the outer refractories.
- 40 10. A furnace structure as specified in claim 9 and wherein said burner ring and anchoring means are exposed in the said air chamber and the latter is provided with an air inlet and an air 45 outlet for the passing of air through the air chamber for cooling effect on the parts exposed therein.
11. A furnace structure comprising, in combination, a frame disposed externally of the furnace 50 chamber, a burner ring supported on the frame, a refractory wall spaced inwardly from the frame to afford an intervening air chamber, outer refractories supported at their outer ends on the burner ring and associated in the form of 55 a collar extending across the air chamber, inner refractories disposed in the wall in the form of a collar the orifice of which together with the orifice of said first mentioned collar afford a continuous burner opening debouching into the furnace 60 chamber, and anchoring means anchoring said inner refractories to the frame to prevent their displacement inwardly out of contact with the outer refractories, said anchoring means permitting said inner refractories limited movement 65 relative to said outer refractories.
12. A furnace structure comprising, in combination, a frame, a refractory furnace wall disposed collaterally of said frame and affording a burner opening, a plurality of inner wedge-shaped refractories disposed in said wall with their divergent faces extending radially from said 70 opening, to form a collar around said burner opening, a wind box disposed at the outer side of the wall and spaced from said inner refractories, 75 a plurality of outer wedge-shaped refractories disposed in complementary relationship with their inner ends adjoining said inner refractories and their outer ends supported by the frame to form a conduit leading from said wind box to said burner opening, and means anchoring the inner refractories to the frame to retain them in association with the outer refractories. 80
13. A furnace structure as specified in claim 12 and wherein said inner refractories are supported by the frame and the superjacent wall refractories are supported by the frame independently of the inner refractories. 85
14. A structural element for furnace wall construction consisting of a refractory tile of wedge-shaped cross section, the longitudinal lateral faces of which converge from the longitudinal outer face, said tile being provided with a pocket adjacent one end, which pocket has its opening in the said outer face for reception of an anchoring member, said tile being formed with a notched portion affording an inset in the side opposite said outer face and said pocket. 90
15. In a furnace structure, in combination, a frame, a refractory wall supported thereon and spaced inwardly therefrom, said refractory wall 100 including refractories arranged therein to encompass a burner opening, a burner ring supported independently of said refractory wall, and outer refractories supported by said burner ring and extending outwardly from said first mentioned refractories to form a sleeve encompassing an outward continuation of said burner opening. 105
16. In a furnace structure having a refractory furnace wall and a burner collar spaced outwardly therefrom and affording a burner opening, the combination of wedge-shaped refractories arranged in said wall to form a refractory collar encompassing a burner opening through the wall in coaxial alignment with said burner opening of the burner collar, an annular member connected to said burner collar and extending toward the refractory wall, a plurality of outer refractories having their outer ends disposed within and supported by said annular member, said outer refractories arranged to form a sleeve positioned coaxially with said burner openings and having its inner end adjoining said refractory collar, a frame disposed externally of the furnace wall, and means anchoring said wedge-shaped refractories 120 to the frame to hold them in association with said outer refractories yet permitting them limited movement relative to one another and to said outer refractories. 115
17. In a furnace structure having a furnace 130 chamber wall and a burner collar spaced outwardly therefrom and affording a burner opening, the combination of inner refractories disposed in said wall to form the boundary of a burner opening through the wall, said burner opening 135 being coaxially aligned with the burner opening of the burner collar, outer refractories arranged to form a sleeve between said burner collar and inner refractories, said sleeve being coaxially aligned with the burner openings of the wall and burner collar and adjoining the burner collar and inner refractories, and means anchoring said inner and outer refractories in 140 assembled position yet permitting them limited relative movement in the assembly. 145
18. In a furnace structure, in combination, a frame, a refractory wall spaced therefrom, inner refractories supported on the frame and arranged in the wall to form a collar, outer refractories supported on the frame and arranged to form 150

- a sleeve extending outwardly from the wall, said collar and said sleeve being coaxially aligned to form the boundary of a burner opening, and means anchoring said refractories in assembled 5 relationship yet permitting them limited relative movement in the assembly. 80
19. In a furnace structure, in combination, a frame, a refractory wall spaced therefrom, an annular member secured to the frame and extending 10 toward the wall, outer wedge-shaped refractories retained in said annular member to form a sleeve, inner wedge-shaped refractories assembled in the wall to form a collar adjoining the inner end of said sleeve, said sleeve and said 15 collar being coaxially aligned, and means anchoring the inner wedge-shaped refractories to the frame to hold them in association with the outer wedge-shaped refractories. 85
20. In a furnace structure, in combination, a frame, outer refractories supported thereby and arranged to form a sleeve extending toward the furnace chamber, inner refractories arranged to form a collar encompassing the inner end of said sleeve and extending therefrom toward the furnace chamber, wall refractories arranged in adjoining association with said inner refractories and supported independently thereof, said sleeve and collar forming the boundary of a burner opening, and means anchoring the inner refractories to the frame yet permitting them limited movement relative to the outer refractories. 90
21. In a furnace structure, in combination, a frame, wedge-shaped refractories supported by the frame and arranged to form a collar affording an approximately circular burner opening, said collar having a polygonal peripheral contour, and refractory wall sections supported by the frame independently of said wedge-shaped refractories in adjoining association with peripheral sides of said collar. 105
22. In a furnace structure having a frame and a burner collar in fixed association with the frame, the combination of an annular member in fixed association with the burner collar, outer 110
- 45
- refractories retained by said annular member in association to form a sleeve extending from the burner collar toward the furnace chamber, a refractory wall spaced inwardly from the burner collar, and inner refractories arranged in said wall to form a refractory collar encompassing the inner end of said sleeve and extending inwardly therefrom, said refractory collar and said sleeve encompassing a passage for admission of fuel into the furnace, and means anchoring the inner refractories to the frame to hold them in assembled relationship with the outer refractories and burner collar yet permitting them limited movement relative thereto in the structure. 115
23. In a furnace structure, in combination, a wall frame, a refractory furnace wall spaced inwardly from said frame and including wedge-shaped refractories supported by the frame and arranged to form a collar encompassing an opening through the wall, the divergent faces of said wedge-shaped refractories extending radially from said opening, and means anchoring said refractories individually to the frame but allowing them limited relative movement in their assembled relationship. 120
24. In a furnace wall structure, in combination, a wall-supporting frame, a wall plate secured thereto, a refractory furnace wall supported on the frame but spaced inwardly therefrom and from said plate to form an intervening air passage, an annular member secured to the plate and extending inwardly therefrom, refractories arranged within said annular member to form a refractory sleeve extending across the air passage, inner refractories arranged in the refractory wall to form 125
- 50
- a collar affording a passage through the wall approximately in coaxial alignment with the aperture of said sleeve, and anchoring members anchoring said inner refractories to the plate to retain them against displacement inwardly or outwardly from the refractory wall yet permitting them limited relative movement in the assembled structure. 130
